SPACING AND SUPPORTING MEANS FOR
BRICK VENEER WALLS

Jerry Horncik, Coraopolis, Pa., assignor, by
mesne assignments, to Starlock Manufacturing
Company, Pittsburgh, Pa., a corporation
of Pennsylvania

Application May 16, 1933, Serial No. 671,333

16 Claims. (CL. 72—26)

My invention refers to improvements in spacing and supporting devices for brick veneer walls designed for application to the surface of a wall, either old or new, for correctly spacing and supporting a continuous series of brick veneer slabs or units.

In this art, a number of comparatively thin slabs are applied to the customary surface of a building, in simulation of an actual brick wall construction, for providing a protecting and ornamental covering therefor, as hereinafter described.

Similar slabs have heretofore been applied in plural number units or sections comprising a series of spaced apart slabs provided with a continuous holding sheet metal backing, either in molded holding engagement with the slabs, or provided with outwardly projecting holding, spacing, and anchoring extensions, and in various other similar ways for the same general purpose and effect.

In my invention I utilize a series of vertically arranged strips or bars to which are applied and secured a series of horizontally arranged supporting and spacing strips having outwardly extending punched out supporting and spacing clip projections, and secured by nails or the like driven through the horizontal and vertical members, into the main wall.

50 In the drawing illustrating one preferred embodiment of the invention:

Fig. 1 is a face view showing the invention as applied;

Fig. 2 is a vertical section on the line II—II of Fig. 1;

Fig. 3 is a horizontal section on the line III—III of Fig. 1;

Fig. 4 is a perspective view showing a portion of one of the horizontal members;

40 Fig. 5 is a sectional detail view illustrating the device in connection with the applied mortar or cement.

In the drawing, 2 represents the main wall of a building provided with clap boards 3 or other surfacing elements, usually of wood or other similar material.

The principal feature of improvement consists of a horizontally laid strip 4 of sheet metal, preferably in channel form, having inwardly extending flanges 5 adapted to be laid against laterally spaced vertical strips 6 of similar metallic shape, or of wood, and secured at intervals by nails 7 driven through both members 4 and 6 at their intersection into the main wall 2.

Strip 4 is provided with outwardly punched ex-

tensions 8, utilizing the middle web portion of the strip, leaving corresponding openings 9 through the web.

Extensions 8 are integrally connected, as at 10, in alternating arrangement as shown, providing a series of upwardly and downwardly arranged spacing and supporting elements, adapted to correctly space the series of brick veneer spaced apart slabs 11 in successive horizontally arranged rows. Such normal arrangement provides the intervening horizontal mortar spaces 12 and alternating vertical spaces 13, in simulation of the face of an ordinary brick wall. Spaces 13 correspond in width to spaces 12, without any holding devices other than the later applied usual mortar filling.

Projections 8, integrally connected at 10, are reinforced by outwardly pressed V-shaped strengthening or stiffening ribs 14, and are bent slightly upwardly and bowed and rounded at their terminals, providing a series of upper and lower spacing and supporting elements for the upper and lower edges of adjacent slabs.

By their integral connection with the web of strip 4, and particularly because of the reinforcing ribs 14, the extensions 8 are quite sufficiently strong and rigid to fixedly support the slabs in position, especially when the grooves 12 and 13 are filled with the usual mortar filling 15. They are also sufficiently resilient to a limited degree to be slightly deflected backwardly, with holding reaction, when the slab 11 is inserted between the clips 8 of any pair of adjacent strips 4.

As shown in Fig. 5, the mortar when applied, and forced through the openings 9, forms a series of interlocking or anchoring dovetail extensions 16, firmly holding the several parts in continuous fixed relation.

The combination of the horizontal strips 4 with the series of vertically arranged strips 6 provides a strong rigid backing construction, firmly secured to the wall 2 by the frequently applied nails 7. Thus when the slabs are applied they are continuously held in position, providing a generally level outer surface and obviating the warped or otherwise objectionable uneven surface effects frequently developed in the several sheet metal backing constructions above referred to.

The strip 4 is made of comparatively thin sheet metal, of ample strength and rigidity and continuous stiffness so as to unyieldingly perform its function throughout the life of the wall.

It is comparatively cheap and light in construction, easily handled and applied, and may be made of any suitable length and other proportions to

adapt it to the usual size and dimensions of a conventional brick slab, or of other similar units of varying dimensions or shape.

The spacing of the slightly resilient projections 5 8 is sufficiently frequent to effect their desired contact and holding function, but may be of course varied as to distance apart, proportions, size, or any other details of manufacture by the skilled mechanic, and all such changes are to be 10 understood as within the scope of the following claims.

What I claim is:

1. In combination with a rear supporting wall, 15 a tile facing support consisting of a series of spaced vertical strips and a series of spaced horizontal strips secured to the wall by nails passing through both at their intersections, and tile spacing and supporting projections extending outwardly from the body of the horizontal strips.

20 2. In combination with a rear supporting wall, a tile facing support consisting of a series of spaced vertical strips and a series of spaced horizontal strips secured to the wall by nails passing through both at their intersections, tile spacing 25 and supporting projections extending outwardly from the body of the horizontal strips, and surfacing slabs mounted on and between the projections of adjacent horizontal strips.

3. In combination with a rear supporting wall, 30 a tile facing support consisting of a series of spaced vertical strips and a series of spaced horizontal strips secured to the wall by nails passing through both at their intersections, tile spacing and supporting projections extending outwardly 35 from the body of the horizontal strips, surfacing slabs mounted on and between the projections of adjacent horizontal strips, and a filling of holding material between the slabs.

4. In combination with a rear supporting wall, 40 a tile facing support consisting of a series of spaced vertical strips and a series of spaced horizontal strips secured to the wall by nails passing through both at their intersections, tile spacing and supporting projections extending outwardly 45 from the body of the horizontal strips, surfacing slabs mounted on and between the projections of adjacent horizontal strips, and a filling of holding material between the slabs having anchoring connection with the horizontal strips.

5. In combination with a rear supporting wall, 50 a tile facing support consisting of a series of spaced vertical strips and a series of spaced horizontal strips secured to the wall and in co-operative fixed relation to each other, and punched out tile spacing and holding projections extending 55 from the body of the horizontal strips for engagement with the edges of applied slabs.

6. In combination with a rear supporting wall, 60 a tile facing support consisting of a series of spaced vertical strips and a series of spaced horizontal strips secured to the wall and in co-operative fixed relation to each other, and punched out tile spacing and holding projections extending 65 from the body of the horizontal strips for engagement with the edges of applied slabs and providing anchoring openings for mortar or the like.

7. A channel shaped sheet metal spacing and supporting strip having its middle web portion provided with punched out resilient bowed projecting clips integrally connected at one side of a 70 clearance opening and having a pressed out reinforcing rib connecting the clip with the web.

8. A channel shaped sheet metal spacing and supporting strip having its middle or web portion provided with punched out resilient bowed pro-

jecting clips and with rounded ends integrally connected with the web at one side of the opening from which the clip is punched.

9. A mounting for tiles and the like comprising a metallic striping consisting in a plurality of independent strip units adapted for mounting in spaced relation on a surface to be tiled, each strip unit having thereon resilient tangs upstanding from the face thereof to define a tileway between cooperating tangs on adjacent mounted strips, whereby in assembly a tile is engaged in mounted position by abutment of its opposite edges against cooperating tangs on adjacent mounted strips and the width of the tileway is determined by the spacing of the strips as mounted.

10. The combination of the claim next preceding in which each strip unit has therein at least two tangs divergent from points adjacent a longitudinal median line of the unit, whereby in assembly of the strips with a plurality of tile courses an interval between tile courses is provided adjacent a longitudinal median line in each strip unit for the reception of mortar, and keys for the anchorage of mortar arranged along said median line.

11. A mounting for tiles and the like comprising a metallic striping consisting in a plurality of independent strip units adapted for mounting in spaced relation on a surface to be tiled, said striping formed of flexible metal and being of inverted trough form to provide flanges along the edges thereof, each strip unit having thereon resilient tangs struck up from the face thereof to define a tileway between cooperating tangs on adjacent mounted strips, whereby in assembly a tile is engaged in mounted position by abutment of its opposite edges against cooperating tangs on adjacent mounted strips and the width of the tileway is determined by the spacing of the strips as mounted.

12. A veneering strip or lath for supporting tile or the like, consisting of a longitudinally channelled member with the channel walls to provide a spacing between the web or body of the channel and a surface against which the strip will rest when mounted for use, the body of the strip having tangs pressed out therefrom to be equally spaced from a longitudinal center line to constitute holding elements for tile, or the like, between said tangs of said strip and similar tangs on adjacently mounted parallel strips, with the strips spaced according to the width of the tile to be accommodated.

13. A strip as in claim 12, in which the tangs are staggered, with alternate tangs on opposite sides of the longitudinal center line, whereby the resultant mortar line width, or spacing between tiles engaged by tangs on opposite sides of the center line, may be made relatively narrow, as desired, by reason of the tangs having freedom of movement to the longitudinal center line.

14. A strip as in claim 12, in which each tang is pressed out from a zone crossing the center line, whereby an opening is formed in the metal along the center line where the tang is removed from the metal, to receive an anchoring key of mortar.

15. A veneering strip for mounting tile or the like, consisting of a relatively long narrow strip-member of resilient material, the middle part of the body of the strip having tangs pressed up and out from the metal from a zone transverse of the longitudinal center line, to permit cooperating strips, when mounted, to be spaced in parallel relation according to a dimension such as the

width of the tile, with an additional allowance for the desired width of mortar line, the tangs having freedom of movement back beyond the center line of their strip to receive a tile when it is 5 pressed into position between the tangs of two adjacent strips, with the strips spaced according to the width of the tile to be accommodated.

16. A veneering strip or lath for use in co-operation with other similar strips to serve as a mounting for tiles and the like, said strip consisting of 10

a unit to be mounted on a surface to be tiled, such unit having thereon resilient tangs upstanding from the body thereof to define a longitudinal tileway parallel to the unit between the tangs of the said unit and co-operating tangs on a parallel adjacently mounted unit spaced therefrom as determined by the width of the tile to be mounted.

JERRY HORNICEK. 10
